DRAPER CORPORATION, OF HOPEDALE, MASSACHUSETTS, A CORPORATION OF
MAINE.

HARNESS STOP-MOTION FOR LOOMS.

1,311,767.

Specification of Letters Patent. Patented July 29, 1919.

Application filed October 18, 1918. Serial No. 253,784.

To all whom it may concern:

Be it known that I, RAPHAEL H. GELINAS, a citizen of the United States, residing at South Hadley Falls, in the county of Hampshire and State of Massachusetts, have invented an Improvement in Harness Stop-Motions for Looms, of which the following description, in connection with the accompanying drawings, is a specification, like characters on the drawings representing like parts.

The invention to be hereinafter described relates to looms, and more particularly to the harness stop motions employed therein for stopping the loom when one of the harnesses drops or falls during the weaving operation.

Should one of the harness supporting or operating means break or become disconnected from a harness while the loom is running great injury to the warp threads controlled by that harness and other parts is liable to occur unless the loom is promptly stopped, and various forms of means have been devised for this purpose. On the other hand should the loom be prematurely started or set in operation before complete repairs have been effected and the parts properly adjusted, warp threads are liable to be broken, imperfect cloth woven, and other objectionable results occur.

One of the important features of the present invention therefore consists in a harness stop motion of simple and novel construction which will insure prompt stoppage of the loom when one or more of the harnesses drops or falls from any cause, such, for instance, as a broken harness support or operating means.

Another important feature of the invention consists in a lock rendered effective when the loom is stopped by a dropped or fallen harness to prevent starting the loom again until the loom fixer or attendant first manipulates the lock to release the loom from its control.

Other important features of the invention consist in the novel combination of parts, which in addition to the above will be herein fully described and then definitely pointed out in the claims.

In the drawings:

Figure 1 is a side elevation and part sec-

tional view with parts broken away showing a loom provided with the present invention; 55

Fig. 2 is a perspective view showing more particularly the harness stop motion devices, the loom frame and other parts being broken away or omitted for clearness of illustration; 60

Fig. 3 is a detached detail of a portion of the lock which prevents starting the loom after it has been stopped by a dropped harness until the lock is manipulated by the loom fixer or attendant. 65

The loom frame may be of usual construction and as shown comprises the side frames 1 connected by cross members 2 and longitudinal members 3. Rising from the cross frames are the standards or arches 4 for sustaining the harness supports as usual. In the present instance of the invention the standards or arches 4 have the cross member 5 which supports the rockers 6 about which the supports or suspending means 7 connected to the harness frames 8 pass, the construction being such that the harnesses, of which there may be any suitable number, may be suspended from the rocker or rockers 6 of appropriate number by the suspending 80 or supporting straps 7, substantially as indicated in Fig. 1. 75

The lower bars of the harnesses have connected thereto the operating connections 9 with the cam actuated levers 10 by which 85 the harnesses are reciprocated as usual in the weaving operation.

Mounted for reciprocating movement toward and from the front of the loom is the lay 11 supported by the lay swords 12, which, 90 as usual are supported for rocking movement at the lower part of the loom frame. The shipper handle 13, as usual, may control the operative and inoperative condition of the loom, the construction being such that 95 when the shipper handle 13 is held in the locking notch of the shipper stand the loom will be in operation and when the shipper is detached from the holding notch it will, under the actuation of spring means, as 100 usual, effect loom stoppage. The construction and operation of the parts thus far described are well understood by those skilled in the art and further elucidation is unnecessary.

A shaft 14 is suitably supported for rock-

ing movement and is provided with one, two or more arms 15 which extend under the series of harnesses as indicated in Figs. 1 and 2, the construction being such that 5 should any one of the harnesses drop or fall by reason of breakage of parts, as for instance its support or suspending strap 7, as indicated in Fig. 1, such harness will engage one of the arms 15 and cause the shaft 14 10 to be moved or rocked. In the present instance of the invention, the shaft 14 is supported in slotted bearings 16 by means of blocks 17 of angular form to engage the slot of the bearing and be restrained from 15 rotative movement therein, the shaft itself being freely rotative in such angular blocks and being normally under the influence of a spring 18, Fig. 2, and tending to turn the shaft 14 in one direction, or clockwise in the 20 present instance. In order that the rock shaft 14 may be sensitive and have its sensitivity adjusted to suit conditions of use from time to time, a counterweight 19 is employed to act in opposition to the spring 18. The 25 counterweight 19 is or may be preferably adjustably mounted on an arm 20 secured to the shaft 14, as indicated in Fig. 2.

The slotted bearings 16 may be sustained by appropriate means but in the present instance are formed upon the fixed arms 21 sustained upon uprights 22 which may be appropriately secured to the floor or machine frame as circumstances may dictate.

When a harness drops by reason of breakage in its supporting or suspending strap and turns the shaft 14, it is desirable that the loom be promptly brought to rest, otherwise great injury is liable to result to the warp threads and other parts. Various 35 means may suggest themselves as appropriate to effect loom stoppage when the shaft 14 is rocked and in the present instance of the invention a finger or stop device is so connected with the shaft 14 that upon rocking movement of the shaft by a dropped harness, the stop device will be moved in the path of a vibrating feeler and arrest such feeler to thereby stop the loom. Secured to the shaft 14 is an arm 23, Fig. 2, the 40 free end of which at 24 engages an arm 25 connected to the stop 26 pivotally supported at 27, the construction being such that upon rocking movement being imparted to the shaft 14, the stop 26 will be moved into the 45 path of a vibrating feeler.

The vibrating feeler may be variously contrived but in the present instance of the invention advantage is taken of the warp stop motion feeler. Looms are usually provided 50 with warp stop motions and in the present instance of the invention the warp threads are shown as sustaining the detectors or drop devices 28 which upon breakage of a warp thread will drop into the path of a 55 vibrating feeler 29 and arrest its motion.

The stop 26 is therefore so disposed with relation to the vibrating feeler 29 that when the rock shaft 14 is turned by a drop harness the finger 26 will arrest vibrating movement of the feeler 29.

The feeler 29 is supported upon a rock shaft 30 having a crank arm 31 to which is connected one end of a link 32, the lower end thereof being pivotally connected at 33 to a lever 34 pivotally mounted at 35 and having its end 36 bearing upon the periphery of a cam 37 mounted upon the under or cam shaft 38. In order to hold the end 36 of the lever against its actuating cam 37 a suitable spring may be employed which, in the present instance of the invention, is indicated at 39, Figs. 1 and 2, one end of the spring being secured to the outer end of the lever 34 and the other end to a fixed bracket 40.

Secured to the rock shaft 30 on which the feeler is mounted and disposed near one side of the loom frame, is an arm 41, Fig. 2, to which is connected a link 42, the other end of which is joined to an arm 43 secured to a short rock shaft 44 appropriately mounted for rocking movement upon the loom frame. On the outer end portion of the shaft 44 is secured a bunter controller 45 having a slot or opening 46 into which projects a pin 47 extending from the side of a bunter 48, the construction being such that as the rock shaft 30 is vibrating or reciprocating the bunter 48 will be appropriately moved. The bunter 48 is carried by an arm 49 pivotally mounted at 50 on the loom frame, the construction being such that the bunter may be moved bodily relative to the short rock shaft 44 and the bunter controller. Connected to the arm 49 is a link 51 the forward end of which is connected at 52, Fig. 2, with a knock-off 53 pivoted at 54 and having an end portion 55 which, when the shipper handle 13 is in its holding notch as usual during loom operation, rests in front of the shipper, the construction being such that should the bunter 48 be moved rearwardly the knock-off 53 will be actuated to detach the shipper from its holding notch and effect loom stoppage either by shipping a belt or disengaging the clutch members as will be readily understood by those skilled in the art.

Mounted for movement with the lay is a part 56, Fig. 1, which, when the bunter 48 fails to be moved by the vibrating feeler, is adapted to engage the bunter on the backward movement of the lay and through the means described effect loom stoppage. Thus, when one of the harnesses drops or falls, due to breakage in one of the harness supports or from any other cause, the rock shaft 14 will be turned and through the described train of mechanism the loom will be promptly brought to rest.

Should the loom be started up again before the broken harness support or other defect has been completely repaired, great injury is liable to result to the warp threads and other parts. The present invention, therefore, contemplates the provision of means for automatically locking the loom when it has been stopped by a fallen or dropped harness and to maintain the loom in such locked condition that it may not be started again until the loom fixer or attendant has manually manipulated the lock to release the loom from its control, whereupon the shipper may be moved as usual and the loom be started.

The lock may be variously contrived, but in the present instance of the invention it comprises interengaging members which, when the rock shaft 14 has been rocked by a dropped or fallen harness, and the finger 26 moved into the path of the vibrating feeler, will maintain the parts in such assumed position and consequently prevent starting the loom until the parts are released from the control of the lock. In the present instance the lock consists, in part, of the arm 20 heretofore referred to, which is extended rearwardly and appropriately formed at its rear portion to constitute a locking arm which, when moved by rocking movement of the shaft 14, will be brought into locking engagement with a coöperating locking catch. Referring more particularly to Fig. 2 the arm 20 is extended rearwardly as at 57 and appropriately turned at 58 to present a locking member 59. The portion 59 may be appropriately bent laterally and then turned upwardly at 60 to embrace the stationary arm 20 and serve as a guide for guiding the movement of the arm 20 as the shaft 14 is rocked. Pivotaly mounted upon one of the uprights or supports 22 at 61 is the locking catch which comprises an arm 62 having an abruptly bent portion 63 and a curved locking portion 64 which may be extended to form an operating lever 65 for disengaging the parts of the lock when the loom fixer or attendant has completed the desired repairs. The arm 65 may appropriately be provided with a small weight 66 which will serve to depress the locking catch into locking position when the locking arm is moved by the rock shaft 14 as indicated in Fig. 1.

When the parts are in unlocked relation and the loom is running the elbow or abruptly bent portion 63 of the locking catch 63 rests upon the bent portion 59 of the locking arm as indicated in Figs. 2 and 3. In order to more effectually maintain the parts in this relation the elbow or abruptly bent portion 63 of the locking catch may be provided with a recess 67 appropriately formed to engage the portion 59 of the locking arm. The parts being in the position as indicated in Fig. 2 and the loom normally running,

should one of the harnesses drop and the rock-shaft 14 be thereby turned, the locking arm 57 will move downwardly and the locking catch 62 will, by reason of the weight 66, turn from the position indicated in Fig. 2 to that of Fig. 1, thereby locking the arm 57 in its lowered position and force the stop 26 in its raised position so that the loom is locked and prevented from being started again until the locking device is manipulated to free the loom from its control.

Applicant believes himself to be the first in this art to provide a lock actuated upon falling of a harness to prevent starting the loom again until after manipulation of the lock by the loom fixer or attendant.

Claims:

1. In a loom, the combination of the harnesses, a rock shaft adapted to be rocked by a dropped harness, a vibrating feeler, a stop finger movable by the rock shaft into the path of and to stop the feeler, a bunter, connections between the bunter and vibrating feeler to cause the bunter to be moved from an operative to an inoperative position by the vibrating movement of the feeler and to be arrested in operative position when the vibrating feeler is stopped by the stop finger, means actuated by the lay for moving the bunter when it is in operative position, and devices connected to the bunter to effect loom stoppage when the bunter is moved by the lay actuated means.

2. In a harness stop motion, the combination of a vibrating feeler, means for arresting the feeler when a harness is dropped, a bunter, a part on the lay adapted to actuate the bunter and effect loom stoppage, a bunter controller connected to the vibrating feeler to move the bunter out of the path of movement of the part on the lay when the feeler is vibrated and to position the bunter for engagement by the part on the lay when the feeler is arrested by a dropped harness to thereby stop the loom.

3. In a harness stop motion, the combination of a vibrating feeler, means for arresting the feeler when a harness is dropped, a bunter, a part on the lay adapted to actuate the bunter and effect loom stoppage, a bunter controller connected to the vibrating feeler to move the bunter out of the path of movement of the part on the lay when the feeler is vibrated and to position the bunter for engagement by the part on the lay when the feeler is arrested by a dropped harness to thereby stop the loom, and a lock acting to maintain the bunter in loom stopping position after the dropped harness is lifted to prevent starting the loom until the lock is moved from its locking position.

4. In a harness stop motion for looms, the combination of a shaft adapted to be rocked by a dropped harness, a vibrating

- feeler, devices connected to the rock shaft for stopping the feeler when the shaft is rocked by a dropped harness, a bunter, a knock-off connected to the bunter, a bunter controller operatively associated with the bunter, connections between the bunter controller and vibrating feeler, and a part on the lay adapted to engage and operate the bunter to effect loom stoppage when the bunter fails to be moved by the feeler.
5. In a harness stop motion for looms, the combination of a vibrating feeler, a stop finger movable into the path of and to stop the feeler by the dropping of a harness, a bunter adapted to be struck and moved by the lay, a bunter controller having a slotted connection with the bunter, connections between the controller and vibrating feeler, and a knock-off device connected to the bunter.
10. In a loom, the combination of the harnesses, a feeler, means for vibrating the feeler, a feeler stop, means actuated by a dropped harness to interpose the stop in the path of the vibrating feeler to stop vibration of the feeler, means connected to the feeler for stopping the loom when vibration of the feeler is stopped, and a latch for locking the feeler stop in the path of vibration of the feeler to prevent starting the loom again when the dropped harness is lifted and until the latch is tripped.
15. In a loom, the combination of the harnesses, a warp stop motion including a vibrating feeler, a feeler stop, means connected to the feeler stop and actuated by a dropped harness to interpose the stop in the path of vibration of the feeler to arrest vibration of the feeler and stop the loom, a latch connected to the feeler stop to lock the stop in the path of vibration of the feeler and maintain the stop in said position when the dropped harness is lifted.
20. In a loom, the combination of the harness and vibrating feeler, a shaft adapted to be rocked by a dropped harness, a stop connected to the shaft and interposed in the path of the feeler to arrest its vibration when the shaft is rocked by a dropped harness, and a lock connected to the stop to hold it in the path of the feeler when the dropped harness is lifted.
25. In a loom, the combination of the harnesses, a shaft having arms extending beneath the harnesses, means for stopping the loom when the shaft is moved from a normal to an abnormal position by a dropped harness, and means acting automatically to lock the shaft in abnormal position after it has been moved by a dropped harness.
30. In a loom, the combination of the harnesses, a shaft having arms extending beneath the harnesses, means for stopping the loom when the shaft is moved from a normal to an abnormal position by a dropped harness, means acting automatically to lock the shaft in abnormal position after it has been moved by a dropped harness, and manual means for releasing the shaft to permit the loom to be run.
35. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
40. A harness stop motion, comprising, in combination, a rock shaft adapted to be rocked by a dropped harness, means operated by the rock shaft for stopping the loom, a locking arm connected to the rock shaft, a locking catch adapted to automatically lock the locking arm when the rock shaft has been rocked by a dropped harness to thereby prevent starting the loom until the locking arm has been released from the catch.
45. In a loom the combination with the harnesses, and a warp stop motion, of means intermediate the warp stop motion and harnesses acting through the warp stop motion to automatically stop the loom upon the falling of a harness upon a portion of said means, and a lock acting automatically upon a part of said means to lock it in loom stopping position and prevent starting the loom again after a fallen harness has been lifted until the parts are released from control of the lock.
50. In a loom, the combination of the harnesses, a warp stop motion including a vibrating feeler, means intermediate the warp stop motion and harnesses including a feeler stop to automatically arrest the movement of the feeler and the loom operation upon falling of a harness upon a portion of said means, and a lock engaging a part connected to the feeler stop to maintain the feeler stop in stopping position until the lock is returned to initial position.
55. In testimony whereof I have signed my name to this specification.
10. In a loom, the combination of the harnesses, a shaft having arms extending beneath the harnesses, means for stopping the loom when the shaft is moved from a normal to an abnormal position by a dropped harness, and means acting automatically to lock the shaft in abnormal position after it has been moved by a dropped harness.
60. In a loom, the combination of the harnesses, a shaft having arms extending beneath the harnesses, means for stopping the loom when the shaft is moved from a normal to an abnormal position by a dropped harness, and means acting automatically to lock the shaft in abnormal position after it has been moved by a dropped harness.
65. In a harness stop motion for looms, the combination of a rock shaft adapted to be moved from a normal to an abnormal position by a dropped harness, means acting automatically to lock the shaft in abnormal position after it has been moved by a dropped harness, and manual means for releasing the shaft to permit the loom to be run.
70. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
75. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
80. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
85. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
90. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
95. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
100. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
105. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.
110. In a harness stop motion for looms, the combination of a rock shaft adapted to be moved from a normal to an abnormal position by the dropping of a harness, a vibrating feeler, a stop finger adapted to be moved into the path of and stop said feeler and the loom when the shaft is moved to an abnormal position, a locking device actuated by movement of said shaft from normal to abnormal position to maintain the stop finger in the path of the feeler after the dropped harness has been raised to operating position to prevent starting the loom, and means connected to the locking device to enable the attendant to unlock the loom that it may be started.

RAPHAEL H. GELINAS.
